UNITED STATES PATENT OFFICE.

OTIS C. SHELDON, OF WORCESTER, MASSACHUSETTS, ASSIGNOR TO SANFORD RILEY STOKER CO., OF WORCESTER, MASSACHUSETTS, A CORPORATION OF MASSACHUSETTS.

AGITATOR FOR STOKER HOPPERS.

Application filed March 1, 1920. Serial No. 362,611.

To all whom it may concern:

Be it known that I, OTIS C. SHELDON, a citizen of the United States, residing at Worcester, in the county of Worcester and 5 State of Massachusetts, have invented a new and useful Agitator for Stoker Hoppers, of which the following is a specification.

This invention relates to a device for breaking up and preventing the formation 10 of arches in a body of coarse material as it is fed down through a hopper.

The principal objects of the invention are to provide an improved device for this purpose which can be connected easily with the 15 feeding mechanism so as to be operated thereby and which will be efficient for the purpose of producing the tendency of the fuel to form arches and breaking up any arches that may be formed; also to provide a 20 construction in which the agitation will occur at the top of the hopper as well as at the bottom, the movement always being in opposite directions at the top and bottom, thus assisting in keeping the material in loose 25 condition especially when applied to a plunger feeding stoker provided with an extension at the top of the hopper. The invention also involves improvements in the shape and construction of the agitator itself, 30 its relation to the hopper, and the means by which the agitator is driven.

Reference is to be had to the accompanying drawings in which—

Fig. 1 is an end view of a hopper for feeding 35 a stoker, showing a preferred embodiment of the invention applied thereto and parts broken away to show its construction;

Fig. 2 is a sectional view of the same through the center of one of the plunger 40 throats;

Fig. 3 is a sectional view on the line 3—3 of Fig. 2;

Fig. 4 is a plan of the operating mechanism taken at the point indicated by the arrow 4 in Fig. 1;

Fig. 5 is an edge view as indicated by the arrow 5 in Fig. 1; and

Fig. 6 is an end view looking in the direction of the arrow 6 in Fig. 5.

Several devices have been invented for 50 keeping the arches broken up in a body of coal fed down a substantially trapezoidal shaped hopper to a series of feeding plungers. Simple as this problem seems it has

been difficult to find a thoroughly practical 55 and efficient device for the purpose.

Although this invention is capable of use in connection with other types of mechanism for feeding coal and other coarse material I have shown it as applied to a hopper 10 of a 60 well known type which feeds coal down into a series of transverse throats 11, at the bottom of which are plungers 12 that force the coal directly into the stoker 13. These plungers, as has been the case heretofore, are 65 operated from a shaft 14 having cranks or eccentrics for operating connecting rods 15 which are connected to the several plungers to give them an alternating motion.

In the present instance I have shown the 70 shaft 14 as provided with a disc 16 on the end supporting a second disc 17 having an eccentric pin 19. This pin is connected with a link 20 which it reciprocates as the shaft 14 rotates. This link transmits motion by a 75 bell-crank 21 to an operating rod 22 which extends longitudinally of the hopper for operating the agitators as will appear. This rod is shown as provided with pairs of pins 23 spaced apart for receiving the ends of 80 the several agitators 24 between them, enough play being allowed to permit of a free motion for swinging the several agitators 24 on their pivots 25 as will be obvious. The number of these agitators preferably is 85

equal to the number of partitions 26 between the several throats 11 in which the plungers 12 are located.

Each of the agitators 24 is made preferably of a single piece of metal and of a general shape similar to the cross section of the hopper. At any rate it is provided with a lower bar 27 which lies over one of the partitions 26 when in neutral position and is parallel with the pivot shaft 25 above which 90 supports the agitator in the walls of the hopper. The agitator is also provided with a top cross bar 28 for agitating the coal near the top of the hopper. This is particularly desirable when the hopper is provided with 95 an extension as 29 because then it is more likely to be substantially full of coal.

The two bars 27 and 28 are connected in any desired way as for example by two members 30 and 31 which are provided with 100 means for pivoting them to the pivot rods or shafts 25, and which may conveniently be made parallel with the front and rear walls

of the hopper 10 to provide for movement along these walls so as to break up the ends of any arches that form in a direction parallel to the movement of the plungers. Such arches are broken up by the movement of this agitator simultaneously with the rocking of the agitator into a position to break up an arch formed in a direction transverse thereto, the two types of arches being indicated in Figs. 2 and 3 respectively.

One of the features of these oscillating frames that is important, is that they give motion in opposite directions in the upper and lower portions of the hopper. Obviously, while the lower parts of the frames below their trunnions are being moved in one direction, the parts of the frames above their trunnions are being moved in an opposite direction and this is a marked advantage in agitating the coal in the hopper. This movement in opposite direction tends to mix up the coal and prevents any possibility of it riding as a mass back and forth on the agitator.

From what has been said it will be seen that a simple device is provided for this purpose and one which will tend to agitate the coal throughout a relatively great area and not merely to break up the arches after they have formed and become wedged into the bottom or more contracted part of the hopper. This is an important feature because it tends to prevent the formation of the arches originally and thus does not necessitate the application of the same amount of power that would be required to dislodge arches that had already formed, composed of lumps crowded and wedged together. This has proved efficient in practice and it will be seen that there is no way in which it is likely to bind, and there are no parts on which an alternate backward and forward bending strain is exerted of a sufficiently high degree to cause crystallization of the metal.

Although I have illustrated and described only a single form of the invention I am aware of the fact that modifications can be made therein and that the invention can be applied to other types of hoppers for feeding coarse material without departing from the scope of the invention as expressed in the claims.

Therefore I do not wish to be limited to all the details of construction herein shown and described, but what I do claim is:

1. In a device for feeding coarse material, the combination with a hopper and means for feeding the material from the bottom thereof, of means in the upper and lower parts of the hopper for simultaneously creating a movement of the material in opposite directions in the upper and lower parts of the hopper.

2. The combination of a hopper for re-

ceiving fuel and feeding it downwardly, and a plunger for positively feeding the fuel at the bottom of the hopper, with a device movable at the bottom of the hopper in a horizontal longitudinal direction transversely to the direction of motion of the plunger, and means movable thereby in the opposite direction for agitating the coal in the top of the hopper.

3. In a device for feeding coarse material, the combination with a hopper, of a frame pivotally mounted in said hopper and having a cross bar at the top located below the top of the hopper for agitating the material in the hopper, and means for oscillating said frame.

4. In a device for feeding coarse material, the combination with a hopper having a slanting wall for feeding the material downwardly, of a frame pivotally mounted in said hopper and having a cross bar at the bottom and one at the top both located below the top of the hopper, and means extending along the hopper for oscillating said frame on an intermediate axis substantially parallel with said bars.

5. The combination with a hopper having an extension at the top with an agitator therein comprising a transverse shaft, and a frame pivoted on said shaft and having a bar near the top of the hopper below said extension and extending from the front to the rear of the hopper, and means for swinging said frame on said shaft.

6. In a device for feeding coal, the combination of a hopper with means at the bottom thereof for discharging the coal therefrom, of a frame located in the hopper, said frame having four sides, two of said sides extending up along the front and rear walls of the hopper and substantially parallel thereto, and the upper and lower sides connecting them within the hopper, and means extending along the hopper for oscillating said frame on an axis between the top and bottom.

7. In a coal feeding device, the combination of a hopper of substantially trapezoidal form in cross section, a series of throats at the bottom extending transversely with respect to the hopper and receiving the coal therefrom, and means at the bottoms of said throats for positively discharging coal therefrom, with a series of agitators pivotally mounted over the partitions between said throats.

8. In a coal feeding device, the combination of a hopper of substantially trapezoidal form in cross section, a series of throats at the bottom extending transversely with respect to the hopper and receiving the coal therefrom, and means at the bottoms of said throats for positively discharging coal therefrom, with a series of agitators pivotally mounted over the par-

titions between said throats, and a rod extending longitudinally of the hopper and having means for loosely engaging said frames and swinging them as the rod reciprocates.

9. The combination with a hopper having transverse throats provided with transverse partitions between them, plungers located in the bottoms of said throats for

discharging material therefrom, a plurality of swinging transverse frames in the hopper over said partitions, and means whereby the frames are swung at the bottom outwardly and upwardly from said partitions into the body of material between the partitions. 10

In testimony whereof I have hereunto affixed my signature. 15

OTIS C. SHELDON.
